UNITED STATES PATENT OFFICE

JULIUS H. MASON, OF DUNCAN FALLS, OHIO

CUTTING MACHINE FOR WOOD GUTTERS

Application filed November 4, 1929. Serial No. 404,707.

This invention relates to wood cutting machines and has for an object the provision of a machine for cutting circular or semi-circular grooves, the invention being especially 5 designed for cutting grooves in the ends of wood gutter sections for splicing the sections.

Wood gutter material may be obtained in lengths of from forty to fifty feet, but is very expensive, the cost being materially increased 10 by transportation, as two cars are required to accommodate lengths of this character. The cost of long lengths of gutter sections therefore is increased considerably over the sixteen to twenty foot lengths.

15 The present invention therefore has for an object the provision of means for splicing the gutter lengths so that not only the sixteen to twenty foot lengths may be economically employed, but much shorter lengths may be 20 cheaply and efficiently joined so that none of the material may be wasted.

Another object of the invention is the provision of a machine by means of which the lengths may be quickly and economically 25 spliced.

With the above and other objects in view, the invention further includes the following novel features and details of construction to be hereinafter more fully described, illustrated in the accompanying drawings and pointed out in the appended claims.

In the drawings:—

Figure 1 is a side elevation of a groove cutting machine constructed in accordance with 35 the invention, a portion of a gutter length being clamped within the machine.

Figure 2 is a top plan view.

Figure 3 is a longitudinal sectional view taken substantially on the line 3—3 of Figure 40 2.

Figure 4 is a section taken substantially on the line 4—4 of Figure 2.

Figure 5 is a side elevation similar to Figure 1 but showing a slightly different form 45 of the invention.

Figure 6 is a section taken substantially on the line 6—6 of Figure 5.

Figure 7 is a fragmentary plan view illustrating the connection between two gutter 50 lengths or sections.

Figure 8 is a section on the line 8—8 of Figure 7.

Figure 9 is a fragmentary perspective view showing one end of one of the gutter lengths or sections.

Figure 10 is a fragmentary elevation of one end of one of the clamping plates.

Referring to the drawings in detail wherein like characters of reference denote corresponding parts, the reference character 10 60 indicates a pair of brackets which may be of suitable size and shape to which are provided upon one of their faces spaced shoulders 11, defining a guide groove for a hanger 12. The brackets 10 are of light construction as are 65 also the hangers 12, and each of these hangers carries at its lower end a collar 13 for the reception of a shaft 14. The hangers are provided with elongated slots 15 for the passage of bolts 16 carried by the brackets 10. 70 Right angularly disposed lugs 17 extend from the upper ends of the hangers and are provided with threaded openings 18 for the passage of set screws 19.

The screws 16 serve to hold the hangers 75 against the faces of the brackets 10, while the screws 19 provide means for adjusting the hangers with respect to the brackets.

Mounted within the collars 13 of the 80 hangers is a shaft 20 which is provided with spaced shoulders 21 against which the collars 13 engage, so that the hangers are spaced upon the shaft. This shaft has its opposite ends threaded as shown at 21' and slidingly 85 mounted upon the shaft is a cutter arm 22, the latter being provided with a sleeve 23 which receives the shafts. A handle 24 is provided upon the arm 22 so that the arm may be conveniently rotated upon the shaft 20.

The cutter arm 22 carries spaced cutters 25, whose blades 26 extend inward toward the brackets 10. These cutters are adjustable longitudinally of the arm 22 through the medium of slots 27 through which the shanks of the cutting elements 26 extend. Nuts 28 which are mounted upon the shanks of the cutting elements serve to hold the cutters in adjusted position.

The arm 22 which carries the cutters is 100 freely movable upon the shaft 21 and in

order to feed the cutters toward the brackets 10, a nut 29 is threadedly engaged with the shaft. This nut has slideable therethrough a headed pin 30 which is adapted to enter a socket 31 provided in the end of the sleeve 23. When the parts are in the position shown in Figure 3 of the drawings, rotation of the arm 22 will move the cutting blades longitudinally of the shaft.

In order to clamp the work in position, there is provided plates 31' which are adapted to be arranged in clamping engagement with opposite sides of the work. These plates are notched as at 32, to engage over ribs 33 provided upon the brackets 10. The plates may thus be adjusted relatively. The outer ends of the brackets have depending therefrom lugs 34, and these lugs are provided with threaded openings for the passage of clamping screws 35 and 36. The screws 35 are provided with handles or wheels 37, while the screws 36 are provided with heads 38 and lock nuts 39.

In the drawings, the invention is shown as arranged for cutting grooves in the ends of wood gutter sections W so that these sections may be spliced. The grooves are adapted to receive curved metal connecting elements 40 which are held in place by any suitable adhesive, such for example, as white lead. The gutter is clamped upon a table or other support 40^a by means of a clamp 41. One end of this clamp is notched to removably engage the shaft 20, while the other end of the clamp carries a clamping screw 42 which engages the bottom of the table or support 40. The clamping screw 36 is adjusted so as to position its plate 31 properly in accordance with the width of the gutter 40 and this screw is then locked in place by the nut 39. The other plate is adjusted against the opposite side of the gutter sufficiently to hold the gutter in place without injury. The hangers 12 may be then adjusted so that the shaft 14 will be concentric with the inner surface of the gutter, and the cutters 25 are then adjusted so as to bring the cutting blades 26 in proper position for the work.

The feed nut 29 is then engaged with the sleeve of the cutter arm and the latter is rotated to feed the blades 26 into the work. After the groove has reached the desired depth, the feed screw may be disengaged from the sleeve of the cutter arm and threaded outward, and the cutting blades may then be withdrawn from the groove.

By threading opposite ends of the shaft 20, the cutters may be positioned at either end of the shaft so that the set screws 36 may at all times be positioned upon the same side of the gutter. This is especially desirable where the gutter is of the Ogee type.

In Figures 5 and 6, the brackets 10^a are provided with outwardly extending arms 42'. These arms have adjustably mounted thereon

collars 43 and 44 which have depending therefrom fingers 45 for engagement with opposite sides of the gutter W. One of these collars carries a set screw 46 and this collar is adapted to be set in position after the manner of the screw 36. The other collar is provided with a thumb screw 47 for manipulation in removing and replacing the gutter. In other respects the construction is the same as that previously described.

The invention is susceptible of various changes in its form, proportions and minor details of construction and the right is herein reserved to make such changes as properly fall within the scope of the appended claims:

Having described the invention what is claimed is:

1. In a machine for cutting grooves, spaced brackets, a shaft disposed transversely of the brackets, a cutter arm rotatably mounted upon the shaft, a cutter carried by said arm and disposed parallel with the shaft, means to feed the cutter longitudinally of the shaft when the cutter arm is rotated, means mounted on said brackets to clamp the work in position, means to center the shaft with respect to the work, and means to adjust the cutter with respect to the work and radially with respect to the shaft.

2. In a machine for cutting grooves, spaced brackets, a shaft disposed transversely of the brackets, a cutter arm rotatably mounted upon the shaft, a cutter carried by said arm and disposed parallel with the shaft, means to feed the cutter longitudinally of the shaft when the cutter arm is rotated, means mounted on said brackets to clamp the work in position, hangers disposed transversely of the brackets and supporting the shaft, means to adjustably secure the hangers to the brackets to center the shaft with respect to the work, and means to adjust the cutter with respect to the work and radially with respect to the shaft.

3. In a machine for cutting grooves, spaced brackets, a shaft disposed transversely of the brackets, a cutter arm mounted for free rotary and sliding movement upon the shaft, a cutter carried by said arm and disposed parallel with the shaft, a feed nut threadedly engaged with the shaft, means providing a detachable engagement between the feed nut and cutter arm to feed the cutter to the work when the arm is rotated, means mounted on said brackets to clamp the work in position, means to center the shaft with respect to the work, and means to adjust the cutter with respect to the work and radially with respect to the shaft.

4. In a machine for cutting grooves, spaced brackets, a shaft disposed transversely of the brackets, a cutter arm rotatably mounted upon the shaft, a cutter carried by said arm and disposed parallel with respect to the shaft, means to feed the cutter longitudinally

of the shaft when the cutter arm is rotated, means mounted on said brackets to clamp the work in position, said means including a combined gauge and clamp and an oppositely located opposed clamp, and means to adjust the cutter with respect to the work.

5. In a machine for cutting grooves, spaced brackets, a shaft disposed transversely of the brackets, a cutter arm rotatably mounted upon the shaft, a cutter carried by said arm and disposed parallel with the shaft, means to feed the cutter longitudinally of the shaft when the cutter arm is rotated, means mounted on said brackets to clamp the work in position, means to center the shaft with respect to the work, means to adjust the cutter with respect to the work and radially with respect to the shaft, and means engagable with the shaft to clamp the machine and work to a support.

10 In testimony whereof I affix my signature.

JULIUS H. MASON.
